ATTORNEY

UNITED STATES PATENT OFFICE.

JOHN HERBERT ELLIS, OF VANCOUVER, BRITISH COLUMBIA, CANADA.

BUCK FOR CLOTHES-PRESSING MACHINES.

Application filed December 11, 1926. Serial No. 154,173.

The invention relates to improvements in bucks for clothes pressing machines, as described in the present specification, and illustrated in the drawings that form part of the 5 same.

The invention consists essentially of the novel arrangement and construction of parts, wherein the buck of a clothes pressing machine is divided into a plurality of individual 10 chambers, an equal number of pipes connecting the individual chambers, respectively with a main pipe, whereby steam may be fed to aforesaid chambers or vacuum withdrawn therefrom, valve means controlling the 15 respective operations, clamp means being provided to prevent, when steaming plush, velvet, or the like, the creeping of steam along the surface of the buck.

The objects of the invention are to construct a buck, for clothes pressing machines, wherein all or a portion only of the buck may be used with equal efficiency for the steaming and pressing of clothes.

Referring to the drawings:

Figure 1 is a plan view with a portion broken away.

Figure 2 is a side elevation view with a portion broken away.

Figure 3 is a detail view of means employed 30 to prevent creeping of steam along surface of buck.

In the drawings:

Like numerals of reference indicate corresponding parts in each figure.

1 represents a buck as used on clothes pressing machines, the said buck comprising a steam chamber 2 for heating the said buck, chambers 3—4—5, and perforated top plate 6, the said buck being mounted on a stand- 40 and 7.

In present construction the vacuum chamber of the buck 1, extends approximately the entire length and breadth of the plate 6, and has been found that when only a portion of 45 the buck is to be used, i. e. the end A for the purpose of steam or pressing a small article such as a coat collar, vest, or the like, there is a great loss in efficiency, due the fact that when steaming, the whole of the buck surface

50 is steamed, when only a portion thereof is required, and when pressing the vacuum is exhausted from the entire surface, whereas if the respective operations were concentrated upon the end A full efficiency would result.

55 To overcome the above mentioned loss in effi-

cency, I provide a plurality of steam or vacuum chambers 3—4—5, each of said chambers being separate individual units, having pipes 8—9—10 connecting the said chambers with a main pipe 11, whereby steam may be admitted to said chambers, or permit of vacuum suction therefrom. It might here be mentioned that in the present construction of bucks a vacuum tank is provided having communication with the main pipe 11, the said 60 main pipe 11 having suitable valve means, controlling the respective operations, and the pipes 8—9—10 carrying valves 12—13—14 which control the aforesaid operations with the respective chambers.

In operation, we will assume that the end portion A of the buck 1 only is required, then the garment to be steamed and pressed is laid upon this portion, which would also be over the chamber 5, the buck 1 having first been heated by means of steam fed through the pipe 15 into the steam chamber 2, the valve controlling the inlet of steam to the main pipe 11 is opened and valves 12—13 remaining closed, the valve 14 is opened and steam admitted to the chamber 5 from whence it will flow through the perforated plate 6 through the garment, thereby steaming the said garment; when only one or two of the chambers are being used it will be understood that padding is placed over the perforated surface of the buck upon which the garment is placed when steaming or pressing and it will be found that steam passing into any one of the chambers will creep upwards and along the buck surface to padding of the unworking surface, therefore, to prevent the said creeping of steam, I provide a clamp 16 which is of triangular formation adapted to be placed over the buck 1 parallel with the divisions of the chambers, and clamped down, whereby the creeping of the steam along the buck surface through the padding aforesaid from the working chamber to the non-working chambers will be prevented, thus eliminating waste 90 of steam, while concentrating all the admitted steam through a predetermined area, resulting in great efficiency in the steaming of a garment.

Having now steamed the garment, I then turn the control valve on the main 11 to a point where the steam is shut off, and the vacuum suction put into action, whereby the said suction is drawn from a predetermined area with full efficiency, for the purpose of 105 110

withdrawal of all surplus steam, at the same time drying the garment quickly.

It will be readily understood that if more area of the buck is desired, it is only necessary to open valve 13 in conjunction with valve 14, or if all the buck is required then all valves, 12—13—14 would be opened whereby steam is admitted to, or vacuum suction obtained, respectively, over all or a greater portion of the buck 1.

The aforementioned steam and vacuum actuating operations being of standard practice and well-known in the present construction of pressing machines for which I do not wish to make claim, to make same clear, I provide a steam pipe 17 having a control valve 18 and a vacuum withdrawal pipe 19 having a control valve 20 connecting with the pipe 11 on one end and with the steam and vacuum tank respectively at the other end whereby the closing of the valve 20 and opening of the valve 18 will permit of steam passing to the main pipe 11 to the desired chamber or chambers through the control valves 12, 13 and 14

as aforesaid or by the closing of the valve 18 and opening the valve 20 vacuum withdrawal may be obtained from any of the desired chambers aforesaid, through the control valves 12, 13 and 14.

By my construction it will be seen that I have increased the efficiency of the buck as at present in use, both for steaming and pressing, at small cost whereby all, or only a pre-determined portion thereof may be employed with a maximum of efficiency.

What I claim is:

In a pressing machine a hollow buck having a perforated top plate, a wall dividing the buck into compartments, means for passing a fluid through any one of said compartments, a padding on said plate and means parallel to a dividing wall and directly thereover adapted to clamp the padding to the plate to prevent the spread of fluid from one compartment to another.

26th November 1926.

JOHN HERBERT ELLIS.
